UNITED STATES PATENT OFFICE.

FRANK E. MARSHALL, OF PORTERVILLE, CALIFORNIA, ASSIGNOR
OF THREE-FOURTHS TO JAMES M. GROVES, OF FARMINGTON,
CALIFORNIA.

SHOE-POLISHING MACHINE.

SPECIFICATION forming part of Letters Patent No. 793,141, dated June 27, 1905.

Application filed December 7, 1903. Serial No. 184,056.

To all whom it may concern:

Be it known that I, FRANK E. MARSHALL, a citizen of the United States, residing at Porterville, Tulare county, State of California, have 5 invented certain new and useful Improvements in Shoe-Polishing Machines; and I do hereby declare the following to be a full, clear, and exact description of the same.

The present invention relates to a certain 10 new and useful apparatus for mechanically polishing shoes, the same comprising a series of pairs of brushes which act successively to clean the shoe to be polished, apply the blacking or polishing material to the surface 15 thereof, and to polish the shoe, combined with a suitable foot-rest which is so arranged that the shoe held thereon is acted upon by each pair of brushes. Preferably each pair of brushes is located in a different horizontal 20 plane, and the foot-rest at predetermined periods is raised by a step movement into different horizontal planes during the work of 25 polishing a shoe, so as to bring the shoe held thereon into the field of action of the various pairs of brushes.

To comprehend the invention, reference should be had to the accompanying sheets of drawings, wherein—

Figure 1 is a side view in elevation of the 30 apparatus. Fig. 2 is a plan view of the mechanism disclosed by Fig. 1 of the drawings; and Fig. 3 is a front view in elevation of the apparatus, the position of the respective pairs of brushes being illustrated, also the rotary 35 brush for polishing the top surface of the shoe.

In the drawings, the numeral 1 is used to indicate any suitable style of frame for the apparatus, which is designed to form a portion of any conventional form of a shoe-polishing stand. Within the frame 1 two pairs of spaced vertical shafts 2 2' are arranged, to each of which shafts three drums or rolls 3 4 5 are secured. Four, or two pairs of vertical shafts and six pairs of drums or rolls are thus 40 provided. Over the drums or rolls work, respectively, the pairs of endless traveling belts 6 7 8, the lower pair of endless belts 6 working over the drums or rolls 3, the second pair of belts 7 working over the middle rolls 10, which brushes apply to the shoe the re-

or drums 4, and the third pair of belts 8 working over the upper rolls or drums 5. Thus three pairs of horizontally-disposed endless traveling belts are provided, to which belts the brushes 9 10 11 are attached. Of these brushes the lower pair constitute the cleaning-brushes for removing the dirt from the shoe to be polished, the middle pair for applying the blacking to the shoe, and the upper pair for polishing the shoe after the blacking has been applied.

Between the endless traveling brushes is located the foot-rest 12, which rest is raised and lowered by means of the crossed levers 13 14. These levers at opposite ends are pivoted between the ears 14' 14'', depending, respectively, from blocks 14³ and 14⁴, upon which the heel and toe portions of the said foot-rest are slidably mounted. The opposite end of the lever 13 is pivotally secured on the rod-support 13', extending between the outwardly-projecting brackets 15 on the frame 1, while the opposite end of the lever 14 is fulcrumed to the bifurcated block 15', upwardly projecting from said frame. The crossed levers 13 14 are centrally connected by means 75 of the pin 16 passing through one lever and working within or through a slot 16' in the opposing lever, Fig. 1 of the drawings. By the employment of the crossed levers 13 14 a lazy-tong connection is made between the 80 foot-rest and the supporting-blocks 15 15'.

The foot-rest is given a step vertical movement to place the same in different horizontal planes by means of a cam 17, secured to a longitudinal shaft 17', working against the under 85 face of the lever 13 during rotation of the said shaft 17'. 17² represents oppositely-disposed brackets mounted upon the frame 1, adapted to support the shaft 17. The movement of the cam 17 is so timed that the foot-rest 12 remains in its lowered position sufficiently long to enable the pair of endless traveling brushes 9 to remove the dirt from the shoe to be polished, when the cam 17, acting upon the lever 13, raises the foot-rest, 90 so as to place the shoe resting thereon between the pair of endless traveling brushes 10, which brushes apply to the shoe the re-

quired blacking or shoe-polishing material. By this time the cam will be so positioned as to impart to the shoe-rest, through its action upon the lever 13, an additional upward movement sufficient to place the shoe held upon the foot-rest between the pair of endless traveling polishing-brushes 11. The foot-rest is held in such position a predetermined length of time, which, as stated, is sufficient to permit of the shoe being perfectly polished by the pair of rapidly-traveling polishing-brushes 11. While the brushes 11 are polishing the shoe the rotary brush 18 bears upon and polishes the upper surface of the shoe. It is believed that this brush may be dispensed with, in which case the length of the bristles constituting the pair of brushes 11 will suffice for this purpose. Still it is deemed advisable to provide for such polishing of the shoe's upper surface, inasmuch as the polishing-brushes 11 may not answer to polish the sides and top of the shoe. After the shoe has been polished the action of the cam 17 upon the lever 13 is such as to allow the foot-rest to move downward or be restored to its original position. The moment the foot-rest proceeds to move downward the user of the machine is made aware that the shoe has been polished, and thus notified to remove his foot from the said foot-rest. However, the drive mechanism for the apparatus may be so governed as to bring the working parts to a state of rest after the shoe has been polished.

The forward pair 2 of the vertical shafts 35 may be said to constitute the drive-shafts for the pairs of endless traveling belts and brushes, which shafts are driven from the main drive or power shaft 19 by means of the bevel-gears 19' thereon, meshing with similar gears 19² secured to the lower end of the vertical shafts 2, Fig. 3 of the drawings. The drive or power shaft 19 is driven by means of any suitable operating mechanism. (Not shown.) To the said shaft 19 is also secured 45 the gear 20, which gear meshes with the gear 20', attached to the lower end of a vertical shaft 21. This shaft at its upper end also carries a gear 22, which in turn meshes with a gear 22', secured to the longitudinal shaft 23, so that the said shaft 23 is driven from the power-shaft 19. This shaft 23 has secured thereto the drum or roll 23', which drum or roll carries the polishing-brush 18. The shaft 23 works in bearings of the brackets 23², projecting upwardly from the frame 1.

Any suitable means may be employed for supplying to the middle pair of brushes the blacking material to be applied to the shoe.

On the power-shaft 19 is located a worm 60 24, which meshes with a worm-wheel 24', secured to a short vertical shaft 24². This shaft 24² carries a bevel-gear 25, which in turn meshes with a bevel-gear 25', attached to the inner end of the cross-shaft 25², Fig. 1 of the drawings. On the outer end of the said shaft

25² is located a worm 26, which meshes with a worm-wheel 26', secured to one end of the longitudinal shaft 17', carrying the operating-cam 17 for the foot-rest. In this manner the rotation of the power-shaft 19 is transmitted 70 to the shaft 17' to operate the cam 17 so as to actuate the said foot-rest at predetermined moments.

No attempt has been made to illustrate the driving mechanism for the power-shaft, for 75 any form of mechanism may be utilized for such purpose.

Having thus described the invention, what is claimed as new, and desired to be protected by Letters Patent, is—

1. An apparatus for polishing shoes comprising a pair of cleaning-brushes, a pair of blacking-supplying brushes, and a pair of polishing-brushes, the respective pairs being arranged above one another, a vertically-movable foot-rest working between the respective pairs of brushes at predetermined moments and mechanism for operating the respective brushes and for imparting movement to the foot-rest. 85

2. In an apparatus for polishing shoes, the combination with adjustable means for holding the shoe to be polished, of a series of pairs of horizontally-disposed brushes arranged above one another which respectively clean the 95 shoe, apply the blacking thereto and polish the same, endless carriers for the respective pairs of brushes, and means for imparting vertical movement to the shoe-rest intermediate the respective pairs of brushes. 100

3. In an apparatus for polishing shoes, the combination with a foot-rest, of means for imparting a vertical movement thereto, means for interrupting the movement at predetermined points in its travel, a series of pairs of horizontally-disposed brushes between which the foot-rest moves, said brushes respectively cleaning the shoe to be polished, applying blacking thereto and polishing the same, and mechanism for imparting movement to said 105 pairs of brushes. 110

4. In an apparatus for polishing shoes, the combination with a vertically-movable foot-rest, of means for imparting a step vertical movement thereto at predetermined intervals, 115 a series of pairs of horizontally-disposed endless traveling brushes between which the foot-rest moves, said brushes respectively cleaning the shoe, applying blacking thereto and polishing the same, a vertically-rotating brush 120 for polishing the upper surface of the shoe, and mechanism for imparting movement to the respective brushes. 120

5. In an apparatus for polishing shoes, the combination with a vertically-movable foot-rest, lazy-tong connection between said foot-rest and the frame of the apparatus, a cam acting on said connection to raise the foot-rest with a step movement and allow the same 125 to lower at predetermined intervals, a series of 130

pairs of endless traveling brushes between which the foot-rest moves, said brushes respectively cleaning the shoe, applying blacking thereto and polishing the shoe, and mechanism for imparting movement to the respective pairs of brushes.

6. In an apparatus for polishing shoes, the combination with two pairs of brushes for respectively applying blacking to the shoe, and 10 polishing the same, of a vertically-movable foot-rest working between the respective brushes, and means for imparting said vertical movement to the foot-rest at predetermined intervals and for imparting movement to the 15 respective pairs of brushes.

7. In an apparatus for polishing shoes, the

combination with a series of pairs of brushes working in different horizontal planes, said brushes respectively cleaning, applying blacking to and polishing the shoes, a movable foot-rest, and means for placing the foot-rest at predetermined intervals into different horizontal planes so as to cause the shoe held thereon to be successively acted upon by the respective pairs of brushes.

20 In witness whereof I have hereunto set my hand.

FRANK E. MARSHALL.
